UNITED STATES PATENT OFFICE.

LOUIS H. PORTER, OF ROCKDALE, TEXAS.

CLIP.

No. 871,888.

Specification of Letters Patent.

Patented Nov. 26, 1907.

Application filed June 5, 1907. Serial No. 377,419.

To all whom it may concern:

Be it known that I, LOUIS H. PORTER, a citizen of the United States, residing at Rockdale, in the county of Milam and State of Texas, have invented a new and useful Clip, of which the following is a specification.

This invention relates to clips.

The object of the invention is to provide a simply constructed, cheap, durable and efficient form of clip that shall be adapted for use as a means for holding loose sheets of paper or plies of fabric assembled, or as a clothes pin or a garment supporter, which shall be easy to manipulate in attachment and detachment, and which will not in any way injure an article in connection with which it is employed.

With the above and other objects in view as will appear as the nature of the invention is better understood, the same consists in the novel construction and combination of parts of a clip as will be hereinafter fully described and claimed.

In the accompanying drawings forming a part of this specification and in which like characters of reference indicate corresponding parts,—Figure 1 is a view in perspective of a clip constructed in accordance with the present invention. Fig. 2 is an edge view thereof exhibiting the clamping members partly opened.

The clip comprises two clamping members 1 and 2 that are herein shown as approximately circular in contour, and two levers or finger grips 3 and 4 that are preferably, though not of necessity, practically elliptical in form, and occupy outwardly-diverging planes relatively to the clamping members. The levers are integral with the clamping members and are joined thereto by inward curved necks 5, between which is disposed the rear portion 6 of the clamping member. This portion 6, as clearly shown in Fig. 1, extends some distance beyond the adjacent peripheries of the clamping members and forms a fulcrum upon which the necks 5 bear, and through the agency of which the resistance to flexing on the part of the clamping members when the levers are operated to open them, is materially reduced. This feature is one of the greatest importance inasmuch as by the pro-

vision of the fulcrum portion, wire of heavier gage may be employed in the construction of the clip than would otherwise be possible, so that the utility of the article will be largely increased as it will have a more extended range of usefulness and a greater adaptability for various applications, as it may be employed as a paper clip, or a clamp for holding plies of textile fabric assembled in being cut or otherwise, as a clothes pin or as a hanger for suspending an article of apparel from a nail or the like.

Another feature of novelty of the invention resides in the shape of the levers 3 and 4 and the utility resulting therefrom. As above stated, these levers are approximately elliptical in contour and are disposed with their perimeters in planes approximately parallel with those of the clamping members in order to present broad bearing surfaces to the fingers of the user, and further to provide loops that may engage with a nail or other projection to hold an article of apparel suspended. It will be noted by reference to Fig. 1 that the terminals 7 of the lever loops 8 bear upon the lever loops 9 at or adjacent to the necks 5, by which arrangement the loops 8 will positively be held against yielding relatively to the loops 9 when the clamping members are flexed in being opened.

The article herein described, while simple in character, will be found of the highest efficiency and durability in use, and owing to the novel manner in which the parts are disposed and coact relatively to each other will impart a range of usefulness not present in ordinary clips of this character.

What is claimed is:—

A clip embodying levers and coiled juxtaposed clamping members, one portion of which projects beyond the peripheries of the other portions and constitutes a fulcrum for the levers.

In testimony that I claim the foregoing as my own, I have hereto affixed my signature in the presence of two witnesses.

L. H. PORTER.
